(57) **CLAIM**

The ornamental design for a communication plug, as shown and described.

DESCRIPTION

FIG. 1 is a top perspective view of a communications plug showing our design with a communications cord;

FIG. 2 is a top perspective view thereof without the cord;

FIG. 3 is a bottom perspective view thereof;

FIG. 4 is a top view thereof;

FIG. 5 is a bottom view thereof;

FIG. 6 is a front view thereof;

FIG. 7 is a rear view thereof;

FIG. 8 is a right side view thereof; and

FIG. 9 is a left side view thereof.

FIG. 10 is a top perspective view of another embodiment of a communications plug with a communications cord;

FIG. 11 is a top perspective view thereof without the cord;

FIG. 12 is a bottom perspective view thereof;

FIG. 13 is a top view thereof;

FIG. 14 is a bottom view thereof;

FIG. 15 is a front view thereof;

FIG. 16 is a rear view thereof;

FIG. 17 is a right side view thereof; and

FIG. 18 is a left side view thereof.

FIG. 19 is a top perspective view of the communications plug showing our design with a communications cord;

FIG. 20 is a top perspective view thereof without the cord;

FIG. 21 is a bottom perspective view thereof;

FIG. 22 is a top view thereof;

FIG. 23 is a bottom view thereof;

FIG. 24 is a front view thereof;

FIG. 25 is a rear view thereof;

FIG. 26 is a right side view thereof; and

FIG. 27 is a left side view thereof.

FIG. 28 is a top perspective view of another embodiment of a communications plug with a communications cord;
